CLAIM

The ornamental design for a display screen with graphical user interface, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever. The FIGURE is a front view of a display screen with graphical user interface, showing the new design. The broken lines shown in the FIGURE are environmental only and form no part of the claimed design. The broken lines showing text form no part of the claimed design. The outer rectangle in broken lines is included to illustrate a portion of a display screen and forms no part of the claimed design. Hatched shading indicates a contrast in appearance.
